UNITED STATES PATENT OFFICE.

JOSEPH KREMENTZ, OF NEW ALBANY, ASSIGNOR OF ONE-HALF TO WALTER N. ESCOTT, OF JEFFERSONVILLE, INDIANA.

PHOTOGRAPHIC CAMERA.

SPECIFICATION forming part of Letters Patent No. 362,978, dated May 17, 1887.

Application filed April 27, 1886. Serial No. 200,366. (No model.)

To all whom it may concern:

Be it known that I, JOSEPH KREMENTZ, a citizen of the United States, residing at New Albany, in the county of Floyd and State of Indiana, have invented certain new and useful Improvements in Photographic Cameras, of which the following is a full, clear, and exact description.

This invention relates to photographic cameras of the class in which a plate-holding box is so combined with the casing that the plates may be exposed and then removed to a plate-holding box without taking them from the camera.

The invention in this particular consists in certain constructions and also combinations of mechanism for facilitating the handling of the plates without disturbing the camera, as I will hereinafter specify and claim.

The invention also relates to a shutter for the lens; and in this particular the invention consists in a snap-shutter constructed and operating substantially as will presently appear and be claimed.

In the accompanying drawings, illustrating my invention, in the several figures of which drawings like parts are similarly designated, Figure 1 is a perspective view with one side partly removed to expose the interior. Fig. 2 is a vertical longitudinal section. Fig. 3 is a vertical transverse section. Fig. 4 is a front view, and Fig. 5 a partly-sectional elevation, of the shutter-operating mechanism. Fig. 6 shows in perspective at the left the focusing-glass holder and at the right a plate-holder; and Fig. 7 is a detail in perspective of the plate-operating mechanism, or "plate-carrier," as I shall hereinafter designate it.

The camera frame or casing A is an oblong box of suitable construction, and is provided with a lens box, B, and dark chamber C, a focusing-door, D, and a central partition, E, the latter dividing the casing into upper and lower compartments, in the former of which the aforementioned partitions are located. In the lower compartment is arranged a plate-holder box, F, provided with horizontal side rails, a, which engage grooves or ways b in the frame, so as to permit said box to be moved back and forth in said compartment. The box F is provided with a series of pockets, G, to receive and hold

upright and separated from one another a focusing-glass, H, and a series of plate-holders, I. The holder for the glass H and the plate-holders consist of metal frames provided with 55 inturned edges c to receive and hold the glass and plate, respectively, (see particularly Fig. 5,) and the upper corners of these holders are provided with laterally-projecting arms d. Vertical ways J are provided in the sides of the 60 frame, which receive and guide the plate-holder carrier, Fig. 7, to enable it to take a holder from the box F and put and hold it in position with respect to the lens for "exposure," 65 technically so called, and thereafter return it to the box and take up another, said carrier being also utilized for moving the focusing-glass into and out of position in the same way. This carrier consists of sliding brackets or bearings e, arranged in the ways J and swiveled 70 to arms f, which are jointed to levers g, pivoted at h to the sides of the frame or casing A at its rear. The levers g have jointed to them certain vertical rods, i, which are suspended from the ends of a crank-shaft, j, borne by the frame 75 or casing A between its cranked ends, and said crank-shaft is connected with an elbow-lever, k, which projects through the rear of the casing and constitutes a handle, which, when pulled outward from the frame, will raise 80 the crank-shaft and series of devices i g f e, and when pushed into the frame will lower these parts. The position of rest of the brackets or bearings e is in line with the arms d d of the plate-holders, and the said arms of one 85 or another of said holders are normally resting within or upon said bearings. (See Fig. 3.) The several holders are successively or promiscuously aligned with these brackets by means of a notched pull-piece, K, attached to 90 the box F and projecting through the front wall of the lower compartment, where it is held by a catch, L, engaging one of its notches, there being a notch for each socket in the said box. The box is movable back and forth in this compartment through the medium of its ways a b, and by an additional rail, M, on the bottom, if desired.

When a plate-holder and its plate have been raised into position for exposure, a slide, N, 100 is pushed in from the rear to go beneath and support said holder, and flat springs O serve

to press against the back of the plate-holder to keep it in position.

My shutter comprises the shutter proper, *P*, hinged at its lower end and provided with a 5 toggle-lever, *l*, which is connected to a shutter-operating slide, *m*, by a rod, *n*, a spring, *o*, acting against the toggle-lever to normally close the shutter. The shutter is held open by a spring-catch, *p*, engaging notches *r* in the 10 edge of the slide *m* against the strain of the spring *o*. A trigger, *s*, instantly releases the catch *p*, and the spring *o* thereupon instantly closes the shutter. It will be observed that my snap-shutter opens and closes, and hence 15 may be opened and closed by one movement of the slide of the toggle-lever, so that its rapidity of working is largely increased.

There are some details of construction fully 20 illustrated in the drawings not here specifically described—for example, the provision at all points for preventing leakage of light, and the notching of the pull *k*, so as to engage a plate on the frame to lock the holder-carrier in raised position for exposure. It may also be suggested 25 that the crank-shaft might be pivoted at, say, points 2, and the bow 3 be extended beyond the frame, or a handle from it project from the frame and be used as an operating device. There is a door, *R*, for the lower compartment 30 which contains the box *F*.

I desire to lay special stress upon the compactness of arrangement of my camera, and also to the fact that by my means and method of operating the plates it is never possible to 35 have a negative "light-struck."

What I claim is—

1. In a camera, an upper and a lower compartment and a plate-holding box arranged within the lower compartment, combined with a plate-holder carrier, *e f g i j k*, adapted to 40 engage the plate-holders in such box and present their plates for exposure in the upper compartment, and thereafter return them to the plate-holder box without moving the camera, substantially as described. 45

2. A camera having a lower compartment provided with horizontal slideways and vertical guides, combined with a movable plate-holder box fitted in said slideways, brackets *e*, arranged to operate in said guides, arms *f*, 50 levers *g*, rods *i*, crank-shaft *j*, and lever *k*, co-operating with said brackets to take a holder from the box, expose it in the upper compartment, and thereafter return it to the box, substantially as described. 55

3. The combination, with the plate-holder carrier having brackets *e*, of the plate-holders having projections *d* to engage said brackets, substantially as described.

4. In a camera, a snap-shutter pivoted at its 60 lower end, combined with a slide, a toggle-lever connecting the slide and shutter, a spring acting upon said shutter to hold it shut, and a catch engaging the slide to hold the shutter open, substantially as described. 65

In testimony whereof I have hereunto set my hand this 23d day of April, A. D. 1886.

JOSEPH KREMENTZ.

Corrections in Letters Patent No. 362,978.

It is hereby certified that in Letters Patent No. 362,978, granted May 17, 1887, upon the application of Joseph Krementz, of New Albany, Indiana, for an improvement in "Photographic Cameras," errors appear in the printed specification requiring the following corrections, viz: In line 14, page 2, strike out the comma after the word "closes" and insert the words *by one passage, from extreme to extreme, of the toggle-lever*, and in line 16, same page, strike out the words "of the toggle-lever," and that the said Letters Patent should be read with these corrections therein that the same may conform to the record of the case in the Patent Office.

Signed, countersigned, and sealed this 24th day of May, A. D. 1887.

[SEAL.]

Countersigned:

BENTON J. HALL,

Commissioner of Patents.

D. L. HAWKINS,
Acting Secretary of the Interior.
